UNITED STATES PATENT OFFICE.

EDWIN N. CHANDLER, OF BROCKTON, MASSACHUSETTS, ASSIGNOR TO SIMPLEX ELECTRIC HEATING COMPANY, OF BOSTON, MASSACHUSETTS, A CORPORATION OF MASSACHUSETTS.

ELECTRICALLY-HEATED BRANDING-HEAD.

1,022,061.

Specification of Letters Patent.

Patented Apr. 2, 1912.

Application filed November 25, 1910. Serial No. 594,011.

To all whom it may concern:

Be it known that I, EDWIN N. CHANDLER, a citizen of the United States, residing at Brockton, in the county of Plymouth and State of Massachusetts, have invented an Improvement in Electrically-Heated Branding-Heads, of which the following description, in connection with the accompanying drawings, is a specification, like letters on the drawings representing like parts.

This invention relates to branding heads adapted to be secured to a press plunger and to receive and hold various kinds of impression dies to produce either raised embossing or intaglio impressions; in the embodiment to be set forth the head is provided with an inclosed electric heater in the form of an embedded resistance element disposed adjacent the die.

20 While the improved branding head is applicable to other and general uses, it has been especially designed for use in a press for stamping impressions on leather goods, as boot and shoe parts.

25 For an understanding of the invention in detail, reference is had to the accompanying drawing, wherein—

Figure 1 shows an end elevation of the branding head; Fig. 2 is a central vertical section on line 2—2, Fig. 1; and Fig. 3 is a view in section showing a modified detail.

The head is composed of heavy plates 1 and 2, shown as square but which may be of any form desired, clamped together by screws or bolts 3. The upper plate 1 has a boss 4 projecting upward, and a socket 5 extending through the plate adjacent one side thereof and this boss, to receive a suitable operating plunger 6, which may be clamped therein as by a usual clamping screw 7. The lower plate 2 has its top dished out to receive a resistance coil 8 embedded in cement or enamel, this typifying any suitable form of electric heating device.

40 An upstanding projection 9, centrally beneath the plunger 6, receives the thrust thereof to prevent injury to the surrounding enamel layer. The operative face of the plate 2 has an undercut channel 10, which may be of circular or other cross section, extending from the opposite side centrally beneath the plunger 6 nearly to the edge of the plate beneath the plunger, such edge being formed with a projecting trans-

55 verse ledge 11 formed as a straight edge.

This ledge as shown projects from the face 2 somewhat less than the thickness of the usual impression die shown at 12, such die typifying any one of a wide variety of widths, lengths, and forms adapted to be 60 clamped on the face of the plate 2 between the ledge 11 and a projection 13 on a follower 14. The follower 14 is slidably held in the undercut channel 10 and is adapted to be forced forward for such clamping action 65 by a screw bolt 15 threaded through a bearing piece 16 fastened as by screws 17 to the plate 2, such bolt having a spurred end 18 to receive an operator.

The die-engaging portions of the ledge 11 70 and the opposed projection 13 may extend out with parallel sides, as shown in Figs. 1 and 2, or they may be undercut as shown at 19, 20 in Fig. 3, to effect dove-tail engagement with a correspondingly formed 75 die 12'.

One of the plates, shown as the plate 2, may be provided with an upstanding plate lug 21 adjacent the resistance coil terminal opening 22 to protect the wire connections 80 from injury.

It is apparent that various minor changes in detail may be made within the scope of the invention in its broader aspects, for example, the backing ledge 11 instead of being a continuous ledge may consist of upstanding lugs equally spaced on either side of the central line of the channel 10.

By this construction a simple, compact branding head is formed, enabling dies of 90 various widths and other dimensions to be clamped to lie against the face of the head substantially centrally beneath the operating plunger and in close proximity to the heating element, whereby the impression is 95 evenly and accurately produced, with an economical expenditure of electric energy for the necessary heating.

The plates 1 and 2 are made of considerable thickness, so as to afford a substantial 100 mass of heat-storing metal, and the resistance element being disposed centrally therein and extending over nearly the entire transverse area thereof, delivers its heat uniformly thereto so that a maximum portion of such heat is conserved and transmitted to the die clamped on the outer face. Further, the resistance element and its bed of enamel are absolutely protected from external injury, while the strut or projection 105 110

9 insures against crushing or mutilation thereof by the operative thrusts of the plunger; at the same time the resistance element can be instantly uncovered, should 5 this be necessary, for repair or inspection thereof by merely removing the fastenings 3.

Having described my invention, what I claim as new and desire to secure by Letters Patent is,

10 1. An electrically heated branding head, comprising a plate, a fixed ledge projecting from one face thereof at one side, a projection adjustable centrally across said plate to co-act with said ledge as a die clamp, an 15 electric resistance element extending in parallelism with said plate to heat a die carried thereby, and a heavy plate or block secured to said first plate having a socket therein substantially opposite a die carried 20 by said first plate, said plates embracing between them said resistance element and together constituting a substantial mass of heat storing metal.

2. An electrically heated branding head, 25 comprising a plate having a fixed ledge at one side, and a ledge to co-act therewith for clamping a die adjustable centrally across a face thereof, a heavy plate or block with a plunger receiving socket therein secured 30 to said first plate so that said socket is at the same side of the head thus formed as said fixed ledge, and an electric resistance element extending flatwise of the head and embedded therein, the two plates forming 35 said head constituting a substantial mass of heat storing metal, the parts being constructed and arranged so as to protect said resistance element from the operative thrusts of a plunger on said head.

40 3. A branding head, comprising a plate, a ledge projecting from the operative face thereof centrally of one side, an undercut channel formed centrally across said plate at right angles to said ledge, a follower adjustable in said channel and held therein by

the under-cut sides thereof to co-act with said ledge to clamp a die, a resistance element lying parallel to said plate and embedded therein adjacent a die clamped thereon, and means to secure a plunger to said 50 plate substantially in line with the die.

4. An electrically heated branding head, comprising a plate having a ledge projecting centrally at an edge of an operative face thereof, an undercut channel extending 55 centrally across the plate at right angles to said ledge, a follower adjustable therein and held by the under-cut sides of said channel and adapted to co-act with said ledge to clamp a die, a resistance element embedded 60 in said plate, and a second plate fixed to said first plate and having a socket to receive an operator.

5. An electrically heated branding head, 65 comprising a pair of plates removably fixed together and constituting a substantial mass of heat-storing metal, one of said plates having its inner face dished out over substantially its entire area, a resistance element embedded therein, and extending in parallelism with a work receiving face of one of said plates, a plunger engaged with and extending through the other of said plates, a projection upstanding from the former plate 70 to receive the thrust of said plunger and protect the embedded resistance element, an undercut channel extending across the outer face of the former of said plates centrally thereof and centrally beneath said plunger, a follower therein and held by the under-cut face of said channel, and means co-operative therewith to clamp dies of varying 75 sizes substantially in line with said plunger.

In testimony whereof, I have signed my name to this specification, in the presence of 85 two subscribing witnesses.

EDWIN N. CHANDLER.
